COLLAPSIBLE SECTIONAL TOP TABLE

Lessing Alch, St. Louis, Mo.

Application April 6, 1945, Serial No. 586,866

5 Claims. (Cl. 311—89)

1

This invention relates in general to certain new and useful improvements in game tables and, more particularly, to relatively large tables for playing table tennis, ping-pong, or any other similar game requiring a sizeable playing area.

With the increase in popularity of indoor games, such as table tennis or "ping-pong" as it is sometimes called, it has become increasingly important and desirable to provide a type of table which may be collapsed or folded up at will and readily stored away when not in use. Because of the relatively large area of playing surface and rigidity of construction usually required, tables heretofore made have been bulky, cumbersome, heavy in weight, and overly expensive.

It is, hence, the primary object of the present invention to provide a game table of the type stated which is sturdy, rugged, and durable, when set up for use, and which may be readily and easily collapsed or folded up and stored away when not in use.

It is a further object of the present invention to provide a collapsible game table which is compact when folded up so that it may be economically packed for shipment from factory or dealer to purchaser and can be conveniently handled for storage when not in use.

It is an additional object of the present invention to provide a game table of the type stated which can be quickly and simply folded up and "rolled away," so to speak, in a suitable closet or storage space.

It is also an object of the present invention to provide suitable hardware for use in constructing a collapsible game table or similar article.

And with the above and other objects in view, my invention resides in the novel features of form, construction, arrangement, and combination of parts presently described and pointed out in the claims.

In the accompanying drawings (four sheets)—

Figure 1 is a top plan view of a game table constructed in accordance with and embodying the present invention;

Figure 2 is a side elevational view of the game table in fully opened or so-called "playing" position;

Figures 3 and 4 are side and end elevational views, respectively, of the game table in collapsed or so-called "folded-up" position;

Figures 5 and 6 are fragmentary sectional views of the game table taken, respectively, along lines 5—5 and 6—6 of Figure 4;

Figures 7 and 8 are side and front elevational views of a modified form of roller bracket forming a part of the present invention;

2

Figure 9 is a fragmentary detail view illustrating, in perspective, the hinge structure employed in the roller bracket shown in Figures 7 and 8;

Figure 10 is a top plan view, partly in section, of another modified form of roller bracket forming a part of the present invention;

Figure 11 is a fragmentary end elevational view of the roller bracket shown in Figure 10;

Figures 12 and 13 are fragmentary side views, partly in section, of the roller bracket of Figure 10 in fully opened and fully closed positions, respectively;

Figure 14 is a perspective view of a further modified form of roller bracket forming a part of the present invention;

Figures 15 and 16 are top plan views of the two complementary stampings forming the principal parts of the roller bracket shown in Figure 14; and

Figures 17 and 18 are, respectively, top and side elevational views, partly in section, of a further modified form of roller bracket forming a part of the present invention.

Referring now in more detail and by reference characters to the drawings, which illustrate practical embodiments of the present invention, A designates a game table comprising two preferably square table-sections 1, 1', respectively including plywood tops 2, 2', having smooth playing surfaces 3, 3', and suitably finished under surfaces 4, 4'. Secured around the outer margins of each of the tops 2, 2', respectively, and projecting outwardly from the under faces 4, 4', are narrow side rails 5, 5', 6, 6', matching end rails 7, 7', and intermediate or abutment rails 8, 8', provided in their meeting faces 9, 9', with a plurality of pairs of matching shallow recesses 10 for receiving pairs of hinges 11 by which the table sections 1, 1', are swingably secured together in such a manner that, when the table A is in fully opened or "playing" position, the playing surfaces 3, 3', will be accurately co-planar and the meeting faces 9, 9', will be in tight abutment, as best seen in Figures 1 and 2.

Swingably mounted in the two outer corners of the table sections 1, 1', are outer legs 12 having conventional break-braces 13 whereby the legs 12 may be optionally disposed in upright position, as shown in Figure 2, or folded down against the under faces 4, 4', and along the respectively adjacent side rails 5, 5', 6, 6', as shown in Figures 3 and 4. Similarly mounted in the two inner corners of the table section 1, are intermediate legs 14 having break-braces 15 and being spaced inwardly from the respectively ad-

ja cent side rails 5, 6, so as to clear the outer legs 12 when folded down, as shown in Figure 4.

Bolted or otherwise rigidly mounted on the under faces 4, 4', of the tops 2, 2', respectively, are pairs of roller brackets B each comprising a mounting block 16 and a bracket-arm 17 secured together by screws 18. The bracket-arms 17 are disposed in endwise abutment against, and extend outwardly beyond, the respective intermediate rails 9, 9', over which they are mounted, having free under faces 19 provided with roller casters 20, the latter being of such size as to project a substantial distance below the intermediate rails 9, 9', when the table A is in "folded-up" position, as best seen in Figures 4 and 5. Consequently, when the table A is "folded-up," it may be easily and conveniently rolled away into a closet or other suitable storage space. In addition, it should be noted that the hinges 11 lie between the roller casters 20, so that the entire weight of the table A becomes a direct downward thrust, and tends to hold the entire structure forcibly in closed or "folded-up" position and prevents the table from accidentally falling open. It should furthermore be noted that the pairs of roller brackets B, which are mounted upon the under face 4 of the top 2, are spaced inwardly from the respective side rails 5, 6, by a greater distance than the corresponding roller brackets B, which are mounted against the under face 4' of the top 2'. Consequently, the several roller brackets B will not interfere with each other when the table A is opened up into playing position, and, when the table A is set up and in use, will be in substantially concealed or out-of-the-way position.

On the under face 4 of the top 2, is a rectangular storage rack C comprising two end members 21, a bottom member 22, and an intermediate partition 23. Nailed or otherwise secured at their ends upon the outwardly presented margins of the end members 21 and partition 23, is a plurality of spaced parallel slats 24, the entire structure being of such size and shape as to provide two compartments c, c', for respectively housing conventional paddles p and ping-pong balls b. It will be noted in this connection that the compartments c, c', are, in a manner of speaking, open-topped when the table is in the collapsed or folded-up position shown in Figure 4, so that the paddles p and balls b may be dropped into the compartments c, c', and will be supported upon the bottom member 22 and held against the slats 24.

In addition, the two net-supporting arms 25 are swingably mounted upon the outwardly presented faces of the side rails 5, 6, adjacent the line of abutment or so-called hinge line between the table sections 1, 1', by means of threaded studs 26 and wing nuts 27. Secured at its ends and extending tightly between the arms 25, is a conventional ping-pong net 28.

When the table A is set up in playing position, the arms 25 may be swung up into the position shown in Figure 2 and tightened in such position by screwing down the wing nuts 27. Preparatory to folding up or collapsing the table, the wing nuts 27 may be loosened and the arms 25 swung down into the position down in dotted lines in Figure 2, in which position the net 28 will lie flat upon the upper face 3 of the table section 1 and will be protectively concealed between the table sections 1, 1', when the table is in folded-up or collapsed position. It will thus be evident that the entire table and all the nec-

essary paraphernalia or appurtenances involved in playing the game of ping-pong are embodied in a single unit which may be readily and conveniently folded up, rolled away, and stored in a closet or other convenient location.

If desired, a modified form of roller bracket B¹ may be employed comprising a fixed hinge leaf 29 having a pair of countersunk apertures 30 for securement upon the under faces 4, 4', of the top sections 2, 2', and a knuckle 31 provided with an axial slot 32 terminating at its upper end in a swing-slot 33 and at its lower end in a reversely bent detent slot 34. Provided for co-operation with the leaf 29, is a swinging leaf 35 having a knuckle 36 provided with an elongated axially projecting pintle 37 sized for snug-fitting rotating disposition within the knuckle 31 and having a radially extending pin 38 sized for free sliding movement within the slot 32. The leaf 35 is provided with countersunk apertures 39 for securement by means of suitable screws 40 to a bracket arm 41 formed of a block of wood which is preferably somewhat smaller in thickness than the width of the abutment rail 9 and is of sufficient width so as to project a substantial distance out beyond the rail 9 when disposed at right angles to the plane of the top 2. On its under face and adjacent its outer end, the arm 41 is provided with a roller caster 20', substantially identical in all respects to the previously described roller caster 20.

It will, of course, be obvious that the table A may be equipped with four roller brackets B¹ instead of the previously described roller brackets B, in which case four roller brackets B¹ are mounted in substantially the same respective positions as the previously described four roller brackets B. When the table A, thus equipped with four roller brackets B¹, is set up in operative position, the pintle 37 is shifted downwardly within the hinge 31 and swung outwardly, so that the pin 38 is engaged in the detent slot 34, in which position the bracket arm 41 will extend downwardly and outwardly at right angles to the plane of the table top and, when the table is collapsed or folded-up, the bracket arms 41 will, in this position, function to support the table in the manner described above. After the table has been collapsed, however, it can be tilted slightly to one side, so that two of the roller brackets will be eased upwardly off of the floor, whereupon the bracket arm 41 can be dropped slightly downwardly to release the pin 38 from the detent slot 34 and permit the bracket arm 41 to be swung inwardly and, at the same time, shifted upwardly, the pintle 37 sliding lengthwise through the hinge 31 and the pin 38 shifting upwardly in the slot 32. Finally, the bracket arm 41 may be swung inwardly against the under face of the table top in the manner shown in dotted lines in Figure 7. Thereupon, the table may be tilted in the opposite direction and the other two roller brackets B similarly disengaged and swung in out of the way, thereby rendering the entire structure much more compact. The swingable roller brackets B¹ have the very important added advantage that the overall table structure can be much more readily and economically boxed for shipping from the factory to the ultimate user. Furthermore, after the table has been rolled away into a closet or storage space, the roller brackets B¹ may be folded up in the manner above described, so that the table will occupy less space and there will be no danger of a person accidentally stumbling over

the extended roller brackets B¹ or shoving some heavy stored object, such as a trunk, against the roller brackets B¹ and breaking or damaging them.

It is also possible to provide a further modified form of roller bracket B² comprising a flat oblong rectangular plate 42 formed of substantially heavy sheet metal and provided along its rearward margin with an integral centrally positioned hinge knuckle 43 for operative securement by means of a hinge pin 44 to a relatively small hinge leaf 45, which is, in turn, rigidly secured to the under face of the table A' by means of wood screws 46. Also formed integrally with, and bent downwardly from, one side margin of the plate 42, is a brace ear 47, and screwed or otherwise fixed to the under face of the table A', is a suitable angular brace ear 48. Operatively secured at its ends to and extending between the brace ears 47, 48, is a conventional break-brace 49, and riveted or otherwise suitably secured to the under face of the plate 42 adjacent its free end, is a caster assembly 50. It will, of course, be understood that the table A' is preferably provided with four roller brackets B² in much the same manner as has been previously described in connection with the table A. Consequently, when it is desired to fold up the table A', the bracket arms will extend outwardly and the folded table structure will be supported from the floor by casters 50 and may, therefore, be rolled away into a suitable storage space. In packaging the table for shipment or for rendering the table more compact when rolled away into a storage space, the roller bracket B² may be folded in against the under face of the table by breaking the brace 49 at its joint in the conventional manner and swinging the plate upwardly into the position shown in Figure 13.

A similar but slightly modified sheet metal roller bracket B³ may also be provided, which comprises two suitably stamped sheet metal plates 51, 52, respectively provided with matching ears 53, 54, 55, 56, 57, and 58, all of which are bent upwardly at right angles to the main plane of the plates 51, 52. The plate 52 is further provided with a plurality of countersunk apertures 59 for receiving screws by which the bracket B³ may be attached to the under face of a ping-pong table. It should also be noted that the distance between the opposed faces of the ears 56, 57, of the plate 52 is slightly greater than the corresponding distance between the bent-up ears 54, 55, of the plate 51, so that the latter may be fitted freely within the former and the ears 54, 56, and 55, 57, respectively, secured together by suitable hinge rivets 60. Finally, a break-brace 61 is operatively secured at its ears to and extends between the bent-up ears 53, 58, and the plate 51 is provided upon its under face with a caster structure 62, all as best seen in Figure 14.

If desired, a roller bracket B⁴ may be provided, which is substantially similar to the previously described roller bracket B³ and includes two companion plates 51', 52', correspondingly similar to the plates 51, 52, except that the plates 51', 52', are provided with complementary interfitting hinge knuckles 63, 63', and are operatively held together by a hinge pin 64.

It should be understood that changes and modifications in the form, construction, arrangement, and combination of the several parts of the game table may be made and substituted for those

herein shown and described without departing from the nature and principle of my invention.

Having thus described my invention, what I claim and desire to secure by Letters Patent is:

5. 1. A game table adapted optionally to be folded up for storage and opened up for use, said table comprising two hingedly connected top sections each provided with collapsible legs for supporting the top sections in horizontal table-forming position, and a plurality of roller means mounted upon the under side of the top sections in substantially concealed position when the top sections are in table-forming position, each roller means including a mounting element fixed upon the under side of a top section, a bracket arm swingably mounted on the mounting element, and a caster mounted on the bracket arm.
10. 2. A game table adapted optionally to be folded up for storage and opened up for use, said table comprising two hingedly connected top sections each provided with collapsible legs for supporting the top sections in horizontal table-forming position, and a plurality of roller means mounted upon the under side of the top sections in substantially concealed position when the top sections are in table-forming position and being adapted to support the table when the latter is folded up, each roller means including a mounting element fixed upon the under side of a top section, a bracket arm swingably mounted on the mounting element, a caster mounted on the bracket arm, and means associated with the bracket arm for optionally holding said arm in two selected positions in relation to the top section, in one of which positions the arm will be disposed inoperatively against the under side of the top section upon which it is mounted and in the other of which positions the caster will be disposed so as to support the table when it is folded up whereby to permit said table to be conveniently rolled away for storage.
15. 3. A game table adapted to be folded and opened-up optionally for storage and for use, said table comprising two top sections each having a flat playing surface, hinge means connecting adjacent margins of said sections together, collapsible legs operably mounted on the undersides of said sections and being adapted to be folded outwardly from said sections for supporting said sections in substantially horizontal position with the playing surfaces in co-planar alignment when the table is in opened-up position, and roller means operatively mounted on the underside of each section adjacent the hingedly connected margins thereof and being spaced laterally outwardly from the hinged margins a substantial distance from the under-face thereof in cantilever relation thereto in such a manner that when the table is folded-up into inoperative position the roller means will support the entire folded-up table in vertical position with its hingedly connected margins disposed upwardly from the floor, said roller means being located a sufficient distance outwardly from the under-surface of the section to provide a bearing upon the floor as the table sections are swung outwardly away from each other into operative position and hold the hingedly connected margins of said sections upwardly from the floor during such opening movement.
20. 4. A game table adapted to be folded and opened-up optionally for storage and for use, said table comprising two top sections each having a flat playing surface, hinge means connecting adjacent margins of said sections together,

collapsible legs operably mounted on the undersides of said sections and being adapted to be folded outwardly from said sections for supporting said sections in substantially horizontal position with the playing surfaces in co-planar alignment when the table is in opened-up position, roller means operatively mounted on the underside of each section adjacent the hingedly connected margins thereof and being spaced laterally outwardly from the hinged margins a substantial distance from the under-face thereof in cantilever relation thereto in such a manner that when the table is folded-up into inoperative position the roller means will support the entire folded-up table in vertical position with its hingedly connected margins disposed upwardly from the floor, said roller means being located a sufficient distance outwardly from the under-surface of the section to provide a bearing upon the floor as the table sections are swung outwardly away from each other into operative position and hold the hingedly connected margins of said sections upwardly from the floor during such opening movement, and means for optionally locking the table sections together when they are folded together into upright position.

5. A game table adapted to be folded and opened-up optionally for storage and for use, said table comprising two top sections each having a flat playing surface, hinge means connecting adjacent margins of said sections together, collapsible legs operably mounted on the undersides of said sections and being adapted to be folded outwardly from said sections for supporting said sections in substantially horizontal position with the playing surfaces in co-planar alignment when the table is in opened-up position, and retractible roller means operatively mounted on the underside of each section adjacent the hingedly connected margins thereof and being spaced laterally outwardly from the hinged margins a substantial distance and being optionally positionable in retracted position against the under-face

of the section and in extended position outwardly from the under-face of the section in cantilever relation thereto in such a manner that when the table is folded up into inoperative position, the roller means will support the entire folded-up table in vertical position with its hingedly connected margins disposed upwardly from the floor, said roller means being located a sufficient distance outwardly from the under-surface of the section to provide a bearing upon the floor as the table sections are swung outwardly away from each other into operative position and hold the hingedly connected margins of said sections upwardly from the floor during such opening movement, said roller means further being retractible to permit the hingedly connected margins of the sections to drop downwardly into unsupported position directly upon the floor with the roller means disposed compactly against their respective sections.
